United States Patent Office

Des. 229,065
Patented Nov. 6, 1973

229,065

CALCULATING MACHINE

Hisashi Maeda, 24 Imazato Yakushido, Nagaokacho,
Otokuni-gun, Kyoto-fu, Japan, and Kenichi Kitazima,
18-45 Imazato, Hikobayashi, Nagaokacho, Otokuni-
gun, Kyoto-fu, Japan

Filed June 20, 1972, Ser. No. 264,571

Claims priority, application Japan Dec. 21, 1971

Term of patent 14 years

Int. Cl. D14—02

U.S. Cl. D26—5 C

Fig. 1.

Fig. 2.

Fig. 3.

Fig. 4.

Fig. 5.

Fig. 6.

Fig. 7.

FIG. 1 is a perspective view of a calculating machine embodying our new design;

FIG. 2 is a top plan view thereof;

FIG. 3 is a bottom plan view thereof;

FIG. 4 is a front view thereof;

FIG. 5 is a rear view thereof;

FIG. 6 is a left side view thereof; and

FIG. 7 is a right side view thereof.

We claim:

The ornamental design for a calculating machine, as shown.
